UNITED STATES PATENT OFFICE.

PAUL GERLI AND GUIDO BLENIO, OF NEW YORK, N. Y.

APPARATUS FOR PURIFYING THE EXHAUST OF INTERNAL-COMBUSTION ENGINES.

1,032,536.

Specification of Letters Patent. Patented July 16, 1912.

Application filed July 28, 1911. Serial No. 641,114.

To all whom it may concern:

Be it known that we, PAUL GERLI and GUIDO BLENIO, respectively a citizen of the United States and Austria-Hungary, and 5 residing at New York, in the county of New York and State of New York, have invented certain new and useful Improvements in Apparatus for Purifying the Exhaust of Internal-Combustion Engines, of which the 10 following is a specification, such as will enable those skilled in the art to which it appertains to make and use the same.

This invention relates to apparatus for purifying the exhaust of internal combustion engines and particularly of automobile engines, and the object thereof is to provide an apparatus of this class through which the exhaust is passed and by means of which objectionable odors are removed 20 from said exhaust, and said exhaust is purified so that when finally discharged into the air it will be in a transparent or substantially transparent condition and free of objectionable odors, carbonic acid gases and 25 other deleterious products produced by the combustion of oil or its derivatives, and with this and other objects in view, the invention consists of an apparatus of the class specified, constructed as hereinafter described and claimed.

The invention is fully disclosed in the following specification, of which the accompanying drawing forms a part, in which the separate parts of our improvement are designated by suitable reference characters in 35 each of the views, and in which:—

Figure 1 is a longitudinal sectional view showing our improved apparatus applied to the muffler of an automobile engine; Fig. 2 40 a view similar to Fig. 1, but showing a modification, and Fig. 3 a partial section on the line 3—3 of Fig. 1 or on the line 3—3 of Fig. 2.

Automobiles, as is well known, use internal combustion engines and all machines of this class are provided with mufflers, and in the accompanying drawing we have shown at *a* a muffler of the class and for the purpose specified, and in the practice of our invention we secure to and beneath the truck 45 of an automobile frame and preferably adjacent to the rear axle thereof below the muffler a tank *b* which, in the form of construction shown in Fig. 1 is divided by vertical partitions *b*², *b*³, *b*⁴ and *b*⁵ into five compartments *c*, *c*², *c*³, *c*⁴ and *c*⁵ and the com-

partments *c*, *c*², and *c*³ are placed in communication by means of ports or passages *c*⁶ and *c*⁷ in the bottom portions of the corresponding partitions.

60

Placed centrally in the compartment *c* is a tube *d* which extends out through the top of said compartment and down to the bottom thereof and is provided with lateral discharges *d*², and a pipe *e* forms a communication between the muffler *a* and the tube *d*, said pipe *e* being connected with or extending 65 into the top of said tube *d*.

In the top portion of the compartment *c*² are downwardly directed tubes *f* which communicate with the compartment *c* through the partition *b*² as shown at *f*², and these tubes *f* extend downwardly a predetermined distance preferably approximately to the horizontal center of said compartment *c*² or 70 above the same, and in the compartment *c*³ are similar tubes *g* which communicate with the compartment *c*² through the top portion of the partition *b*³ as shown at *g*², and said tubes *g* also extend downwardly and open 75 downwardly to the same extent and in the same manner as the tubes *f*.

In the top portion of the partition *b*⁴ is an aperture *h* forming a communication between the compartments *c*³ and *c*⁴ and in the partition *b*⁵ is a similar aperture *i* forming a communication between the compartments *c*⁴ and *c*⁵. Placed in the central portion of the compartment *c*⁴ is a rotary fan *j* and in the compartment *c*⁵ and preferably in the bottom portion thereof is a similar rotary fan *k*. We also preferably place in the bottom portion of the compartment *c* stirring devices *m* which may be made in the form of fans or of any other shape, and in the top 80 of the compartment *c* is a filling orifice *n* and in the bottom thereof a discharge orifice *n*², said orifices being preferably closed by threaded plugs, and in the bottom of the compartment *c*⁴ is a drip or condensation 85 discharge *n*³, while the compartment *c*⁵ is provided in the bottom thereof with numerous perforations *n*⁴.

In practice a suitable disinfecting and purifying solution *o* is placed in the compartment *c* and flows into the compartments *c*² and *c*³ and enough of this liquid is preferably employed to fill said compartments from one-third to one-half of their capacity.

105
110
110
In the use of this apparatus the exhaust from the muffler *a* passes through the tube

e down through the tube *d* and is discharged at the bottom of said tube into the liquid *o* through which it passes upwardly into the top of said compartment, from 5 which it passes through the tubes *f* into the compartment *c*² and is directed downwardly onto the surface of said liquid, and said exhaust then passes into the compartment *c*³ through the tubes *g* from which it is discharged downwardly onto the surface of the liquid in said compartment after which, 10 it passes into the compartment *c* through the port or passage *h*, and from which compartment *c* it passes into the compartment *c*⁵ through the port or passage *i* and is finally discharged from the bottom perforations *n*⁴ in a pure and transparent or approximately transparent condition. In this 15 operation, the stirrers or fans *m* in the compartment *c* agitate the liquid *o* therein and facilitate the passage of the exhaust upwardly therethrough, and the fans *j* and *k* serve to break up and agitate the exhaust as it passes through the compartments *c*⁴ 20 and *c*⁵ and to remove therefrom any steam or vapor which may remain therein.

In the construction shown in Fig. 2 the compartments *c*³ and *c*⁴ are omitted and only the compartments *c*, *c*² and *c*⁵ are employed. In this construction the agitators or fans *m* are also omitted, but it will be understood that they may be employed if desired. The compartment *c*⁵ in this form of construction is also provided in the bottom thereof with a drip or condensation discharge *p*, and the operation will be readily understood to be the same as with the construction shown in Fig. 1, the only difference being that the exhaust passes 35 directly from the compartment *c* into the compartment *c*² from which it passes into the compartment *c*⁵.

Our invention is not limited to the use of the tubes *f* and *g* in the construction 40 shown in Fig. 1 nor to the tubes *f* in the construction shown in Fig. 2, all that is necessary in this connection being to provide devices of suitable form or construction which will convey the exhaust from 45 one of said compartments into another and discharge it onto the top of the liquid in said compartment, this operation serving to condense the exhaust and to clarify it much more effectively than could be accomplished 50 by discharging said exhaust into said compartments without directing onto or into the liquid.

The solution *o* may consist of any of the well known disinfecting liquids, but is preferably composed of chlorid of magnesium, chlorid of calcium and chlorid of zinc combined in the usual manner.

The automobile is not shown for the reason that it forms no part of our invention, 60 it being deemed sufficient to indicate the

muffler of the engine and the form of our improved purifying apparatus and to describe the method of its operation, and it will be understood that the apparatus may be applied to or connected with the truck 70 frame of the automobile in any desired manner.

It will be understood that while we have described the parts *j*, *k* and *m* as fans, any suitable agitators may be employed and it 75 will also be understood that the agitators or fans *j*, *k* and *m* may be driven in any desired manner, and from the foregoing description it will be seen that the compartment *c* is the inlet compartment of the apparatus or the tank *b*, while the compartment *c*⁵ is the discharge compartment.

Having fully described our invention what we claim as new and desire to secure by Letters Patent, is:—

1. An exhaust purifier for use in connection with automobile internal combustion engines, comprising a tank divided by transverse partitions into two end compartments and an intermediate compartment, 90 one end compartment constituting an inlet compartment and the other an outlet compartment, the inlet compartment being provided with a tube which communicates with the bottom portion thereof and which is 95 adapted to be placed in communication with the muffler of the engine, said inlet and intermediate compartments being also in communication at the bottom thereof and at the top portion thereof, and the intermediate 100 compartment being in communication with the top portion of the outlet compartment.

2. An exhaust purifier for use in connection with automobile internal combustion engines, comprising a tank divided by transverse partitions into two end compartments and an intermediate compartment, one end compartment constituting an inlet compartment and the other an outlet compartment, the inlet compartment being provided with a tube which communicates with the bottom portion thereof and which is adapted to be placed in communication with the muffler of the engine, said inlet and intermediate compartments being also in communication at the bottom thereof and at the top portion thereof, and the intermediate compartment being in communication with the top portion of the outlet compartment, and said outlet compartment being provided 110 with an agitator and with a discharge.

3. The combination with the muffler of an automobile internal combustion engine, of an exhaust purifier comprising a tank located below the muffler and divided by transverse partitions into two end compartments and an intermediate compartment, one end compartment constituting an inlet compartment and the other an outlet compartment, said inlet and intermediate 125

compartments being in communication both at the bottom and the top thereof, the intermediate and outlet compartments being in communication at the top thereof, and 5 said outlet compartment being provided with a discharge, and means for placing the muffler in communication with the bottom of the inlet compartment.

4. The combination with the muffler of an automobile internal combustion engine, of an exhaust purifier comprising a tank divided by transverse partitions into two end compartments and an intermediate compartment, one end compartment constituting an inlet compartment and the other an outlet compartment, said inlet and intermediate compartments being in communication with each other both at the top and bottom thereof and the intermediate compartment 15 being in communication with the top portion of the outlet compartment, and said outlet compartment being provided with a discharge and with an agitator, and means for placing the bottom portion of the inlet 20 compartment in communication with the muffler.

5. An exhaust purifier for internal combustion engines comprising a tank divided by transverse partitions into two end and intermediate compartments, one end compartment being a discharge compartment and the other an inlet compartment, the discharge compartment being provided with discharge perforations, and the inlet compartment being provided with a tube which opens out through the top thereof and discharges into the bottom portion thereof, two of the intermediate compartments being in communication with each 40 other and with the inlet compartment both at the top and bottom thereof, the compartment adjacent to the discharge compartment being in communication with said discharge compartment and with the top 45 portion of the adjacent intermediate compartment, the discharge compartment and the compartment adjacent thereto being provided with agitators, and the bottom of the inlet compartment being also provided 50 with agitators.

6. An exhaust purifier for internal combustion engines of automobiles, comprising a tank divided by transverse partitions into two end compartments and intermediate compartments, one end compartment constituting an inlet compartment and the other end compartment a discharge compartment, the intermediate compartments adjacent to the inlet compartment being in communication therewith and with each other at the bottom thereof and also at the top thereof, and the intermediate compartments adjacent to the discharge compartment being in communication therewith, at the top thereof and said discharge compartment being also provided with a discharge, and means for placing the bottom portion of the inlet compartment in communication with the muffler of the engine. 55

7. An exhaust purifier for internal combustion engines of automobiles, comprising a tank divided by transverse partitions into two end compartments and intermediate compartments, one end compartment constituting an inlet compartment and the other end compartment a discharge compartment, the intermediate compartments adjacent to the inlet compartment being in communication therewith and with each other at the bottom thereof and also at the top thereof, and the intermediate compartments adjacent to the discharge compartment being in communication therewith, at the top thereof and said discharge compartment being also provided with a discharge, means for placing the bottom portion of the inlet compartment in communication with the muffler of the engine, and said inlet and outlet compartments being also provided with agitators. 70 80 85 90

In testimony that we claim the foregoing as our invention we have signed our names in presence of the subscribing witnesses this 27th day of July 1911.
